(57) **CLAIM**

The ornamental design for a candle holder, as shown and described.

DESCRIPTION

FIG. 1 is a perspective view of a candle holder showing my new design;

FIG. 2 is a front view thereof; a rear view, a left side view, and a right-side view being the same thereof;

FIG. 3 is a top view thereof;

FIG. 4 is a bottom view thereof; and,

FIG. 5 is another perspective view thereof.

The candle holder is shown with a symbolic break in its length. The appearance of any portion of the article between the break lines forms no part of the claimed design.
